CLAIM

The ornamental design for the garment sizer ring, as shown and described.

DESCRIPTION

FIG. 1 is a perspective view of the garment sizer ring showing the new design;

FIG. 2 is a front view of the new design;

FIG. 3 is a rear view of the new design;

FIG. 4 is a left view of the new design;

FIG. 5 is a right view of the new design;

FIG. 6 is a top view of the new design;

FIG. 7 is a bottom view of the new design;

FIG. 8 is a perspective view of the garment sizer ring, shown in condition of use; and,

FIG. 9 is another perspective view of the garment sizer ring, shown in condition of use.

The broken lines shown in the drawing disclosure are for illustrative purposes only and form no part of the claimed design.
